(No Model.)

F. WITHERSPOON.

CLOCK STRIKING MECHANISM.

No. 326,825.

Patented Sept. 22, 1885.

UNITED STATES PATENT OFFICE.

FRANK WITHERSPOON, OF PARIS, TEXAS.

CLOCK-STRIKING MECHANISM.

SPECIFICATION forming part of Letters Patent No. 326,825, dated September 22, 1885.

Application filed May 9, 1885. (No model.)

To all whom it may concern:

Be it known that I, FRANK WITHERSPOON, a citizen of the United States, residing at Paris, in the county of Lamar and State of Texas, have invented certain new and useful Improvements in Clock-Chimes; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of a front view. Fig. 2 is a side elevation. Fig. 3 is a similar view. Fig. 4 is a front view, showing a modification. Figs. 5, 6, 7, 8, 9, 10, and 11 are modifications.

This invention relates to clock-chimes; and it consists in the novel construction and combination of parts, as will be hereinafter fully described, and particularly pointed out in the claim.

Referring by letter to the accompanying drawings, A A' A^2 A^3 designate four bells placed one within another, or they may be placed at convenient places within the clock. These bells are tuned to certain notes corresponding to given notes in the musical scale—as, for instance, the first, third, fifth, and eighth of any key for one chime, or two notes or combination of notes above, below, or in the octave, and in any key, as C major, C minor, A major or A minor, or any other required combinations of two or more notes corresponding to given notes on the piano-forte—that will produce melody or harmony in the tones.

B designates the striking side of an ordinary weight or spring clock. The wheel C is provided with pins to engage the lever-arm d , as in the ordinary striking clock. d is a lever, which, being raised by the detent-pins, raises the hammers e at A and releases them to strike the bells. The hammers may be fastened to a single arbor, or to a single piece, c , and branch out from each other; or each hammer may have its individual arbor. In some instances it may be desirable to strike all of the bells at the same time. Then it will only be necessary to have a single arm, a , connected with the rock-shaft C , and pro-

vided with as many branches or auxiliary arms c' having hammers d' as there are bells to be struck. In either construction the hammers are operated by a wheel, C , of the clock mechanism, having pins H' , which engage the lever d of the rock-shaft b . Where the number of hammers and bells are increased, and it is desired to strike the bells alternately, the 55 number of shafts must be equal to the number of hammers. For example, suppose the chimes are to strike 8 o'clock. Then the hammers d , Fig. 4, will strike as follows: first stroke, No. 1 strikes; second stroke, Nos. 65 1 and 2 strike; third stroke, Nos. 1, 2, and 3 strike; fourth stroke, Nos. 1, 2, 3, and 4 strike; fifth stroke, Nos. 1, 2, 3, 4, and 5 strike; sixth stroke, No. 1 strikes; seventh stroke, Nos. 1 and 2 strike; eighth stroke, 7c Nos. 1, 2, and 3 strike. The wheel C is made with the detent-pins H' , for engaging the hammers all on one side of the wheel, and the pins H' are all of the same length, but at different distances from the axis of the wheel; or I 75 may make the wheel C with the detent-pins on both sides of the wheel of the same length, and at equal distances from the axis of the wheel, or of different lengths at equal distances from the axis of the wheel, Fig. 5, or 80 same length at unequal distances from the axis of the wheel, or of different lengths at different distances from the axis of the wheel.

I may employ one wheel, or two or more wheels, on the same or on different pinions or 85 shafts, as shown in Fig. 3, with detent-pins arranged in them, as before described.

In Fig. 8 the mechanism is illustrated that is used to ring the bells in various combinations—as, for instance, first, third, fifth, 90 seventh, ninth, &c., first stroke; second, fourth, sixth, eighth, tenth, &c., second stroke; first, fifth, ninth, thirteenth, &c., third stroke; eighth, fifth, fourth, third, &c., fourth stroke; tenth, eighth, seventh, fourth, 95 first, &c., fifth stroke, &c.; or arranged to strike chords and parts of chords corresponding to the chords in any given key on the piano-forte; or, first stroke, first, fourth, sixth, and eighth of any octave; second stroke, 100 first, third, fifth, and eighth of any or same octave; third stroke fills out or continues the chords or repeats any part of above.

The wheel C may be provided with any

number of projections like teeth, either on the face or side of the wheel, to engage the hammer-wires. The wheel C may be made in the shape of a long cylinder, and provided with 5 pins on its surface for engaging the hammer-wires, and arranged to play any chord or part of chord, or any tune or part of tune, or any notes that may be selected tuned to correspond with any note or notes on the piano-forte. The projections on the wheel C and the hammer-wires may be made straight, or one straight and one bent, or both bent so as to engage each other, or the hammer-wires may be made to interlock or engage each 15 other, so that one may be raised without raising the other, or all may be raised by only raising one.

Having thus fully described my invention, what I claim as new, and desire to secure by Letters Patent of the United States, is— 20

The combination, with the chime of bells in the clock-case, of the wheel C, having the lateral pins, the rock-shaft, a lever extending from the rock-shaft and engaging the said pins, and the hammer-arms respectively connected with the rock-shaft by the short arm a, substantially as shown and described. 25

In testimony whereof I affix my signature in presence of two witnesses.

FRANK WITHERSPOON.
